(57) CLAIM

The ornamental design for a cleaning brush for golf club head, as shown and described.

DESCRIPTION

FIG. 1 is a Front view of a cleaning brush for golf club head showing my new design;

FIG. 2 is a Rear view thereof;

FIG. 3 is a Left side view thereof;

FIG. 4 is a Right side view thereof;

FIG. 5 is a Top plan view thereof;

FIG. 6 is a Bottom plan view thereof;

FIG. 7 is a Perspective view thereof;

FIG. 8 is a perspective view shown in the condition of use with one brush head out.

FIG. 9 is a perspective view shown in the condition of use with two brush heads out.

FIG. 10 is a perspective view shown in the condition of use with all the brush heads out; and,

FIG. 11 is a perspective view shown in the condition of use with one brush head out.

The broken lines shown in the drawings depict portions of the cleaning brush for gold club head that form no part of the claimed design.

1 Claim, 11 Drawing Sheets
